GRIP FOR HANDLE BARS

Arthur L. Morris, 6117 N. Haven Drive,
North Highlands, Calif. 95660

Filed Feb. 15, 1972, Ser. No. 226,641

Term of patent 14 years

Int. Cl. D12—71

U.S. Cl. D90—11

FIG. 2

FIG. 1

FIG. 3

FIG. 4

FIG. 1 is a side elevational view of a grip for handle bars showing my new design;

FIG. 2 is a top plan view thereof;

FIG. 3 is an end elevational view taken from the left of FIG. 1; and

FIG. 4 is an end elevational view taken from the right of FIG. 1.

I claim:

The ornamental design for a grip for handle bars, substantially as shown.
